CLAIM

The ornamental design for a wiper sleeve, as shown and described.

DESCRIPTION

FIG. 1 is a perspective view of a wiper sleeve showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of FIG. 4; and

FIG. 9 is an enlarged view of an area "A" shown in FIG. 1
FIG. 10 is an enlarged view of an area "B" shown in FIG.
6; and,

FIG. 11 is a reference view showing the wiper sleeve.
In the drawings, the dash-dash broken lines depict environment subject matter only and form no part of the claimed design. In FIGS. 1 and 6 the short-dash-long-dash lines depict boundaries of the partial views and form no part of the claimed design. In FIGS. 1, 2, 3, 6, and 7, the dot-dash lines indicate a symbolic break along the length of the wiper sleeve and form no part of the claimed design. The appearance of any portion of the article between the break lines forms no part of the claimed design.
